(57) **ABSTRACT**

An apparatus of a sustain driver in an AC-type plasma display panel having an energy recovery unit, comprising: a first drive unit for driving one electrode of a panel capacitor to a sustain voltage or a ground voltage; a second drive unit for driving another electrode of the panel capacitor to a sustain voltage or a ground voltage; and a common energy recovery unit. The common energy recovery unit includes: an inductor connected to the one electrode of the panel capacitor and form a L-C resonance circuit with the panel capacitor; a first and second external capacitors connected in series between the power source of the sustain voltage and the ground; and a switch unit for selectively switching the L-C resonance circuit and the first and second external capacitors during the charge and discharge operation of the panel capacitor.

**AC-TYPE PLASMA DISPLAY PANEL
HAVING ENERGY RECOVERY UNIT IN
SUSTAIN DRIVER**

FIELD OF THE INVENTION

The present invention relates to a plasma display panel technology; and, more particularly, to an ac-type plasma display panel having an energy recovery unit in a sustain driver.

A plasma display panel (PDP) is a device for displaying a picture and it has been known as a gas discharge display device. Discharge gases, such as Kr and Xe, are filled up between upper and lower panels of the plasma display panel, and an ultraviolet ray generated through the gas discharge exciting red, green and yellow fluorescents, which are formed at least one of the upper and lower panels thereby to generate visible lights.

The PDP is classified into a DC type and an AC type. In the DC type PDP, electrodes for applying voltage to the panel is exposed directly to the discharge gas so that a current directly flows between electrodes in order to form the plasma. Therefore, it is advantageous that the structure is relatively simple. On the other hand, it has disadvantage that the external resistor has to be placed to limit the current. In the AC type PDP, the electrodes are covered with the dielectric substances so that the electrodes are not exposed directly to the discharge gas in order to flow a displacement current. The AC type PDP has longer life span, compared with the DC type PDP, because the electrodes of the AC type PDP can be protected from an ion impact by covering the electrodes with the dielectric substances to limit the current naturally. The AC type PDP can be classified into an opposite discharge type and a surface discharge type. The opposite discharge type has the disadvantage that the life span is shortened by the degradation of the fluorescent substances owing to the ion impact. In the surface discharge type, on the other hand, the discharge is generated near the front panel opposite to the fluorescent substances in order to minimize the degradation of the fluorescent substances, therefore, the surface discharge type is adopted to most of the PDP manufacturing processes.

In the AC type PDP, the high voltage has to be applied continuously and alternately between the sustain electrodes (X electrode and Y electrode) in the discharge cell during the operation of the PDP. Therefore, the dielectric substances are spread over the sustain electrodes so that a panel capacitor exists between X electrode and Y electrode.

In order to alternatively apply the positive and negative high voltage between the sustain electrodes during the operation of the PDP, the charge and discharge operations of the panel capacitor has to be performed. However, the power is consumed considerably by the panel capacitor during the charge and discharge operations, and the power loss problem of a panel drive circuit is generated because the capacitance of the panel capacitor is increased in proportion to the size of the panel.

In order to solve the power loss problems in the panel drive circuit, an energy recovery unit is adopted to the conventional panel drive circuit. In the energy recovery unit, an inductor for forming a LC resonance circuit with the panel capacitor is used to recover the energy loss during the discharge of the panel capacitor. The energy is stored in the inductor through the recovery, and the stored energy is used during the next charge operation of the panel capacitor to reduce the power loss.

A conventional circuit structure of a Weber-type sustain driver in the PDP having an energy recovery unit is shown in FIG. 1.

Referring to FIG. 1, a sustain driver, in the PDP having the energy recovery unit, includes a first and second sustain drivers **100** and **200** which are connected across a panel capacitor C_p .

Each sustain driver **100** and **200** includes a driving unit **12** and **22** and an energy recovery unit **10**. The driving unit **12** and **22** drive the panel capacitor C_p to a sustain voltage V_{sus} or the ground voltage. The energy recovery units **10** and **20** recover the energy loss caused during the discharge operation of the panel capacitor C_p and provides the recovered energy to the panel capacitor C_p during the next charge operation.

The first and second sustain drivers **100** and **200** have symmetrical configuration across the panel capacitor C_p . During the charge and discharge operations, the voltage V_p of the panel capacitor C_p is swung to positive and negative voltage by the first and second sustain drivers **100** and **200** operating alternatively with each other.

The driving unit **12** of the first sustain driver **100** includes a first switch **S1** and a second switch **S2**. The first switch is connected to a power source of the sustain voltage V_{sus} and the panel capacitor C_p and transfers the sustain voltage to the panel capacitor. The second switch **S2** is connected the ground and the panel capacitor C_p and transfers the ground voltage to the panel capacitor. The driving unit **22** of the second sustain driver **200** also includes two switch **S5** and **S6** as in the driving unit **12** of the first driving unit **100**.

The first energy recovery unit **10** in the first sustain driver **100** includes an inductor L_r , an external capacitor C_e , third and fourth switches **S3** and **S4**, and first and second diodes **D1** and **D2**. The second energy recovery unit **20** of the second sustain driver **200** also includes the same element as in the first energy recovery unit **10** of the first sustain driver **100**.

The inductor L_r is connected to the panel capacitor C_p for operating the panel capacitor C_p with a half resonance. The external capacitor C_e stores the energy recovered by the resonance operation of the inductor L_r and the panel capacitor C_p . The third and fourth switches **S3** and **S4**, coupling in parallel, are connected to the external capacitor C_e for switching an energy recovery path. The first and second diodes **D1** and **D2**, coupled in parallel and to reversal direction with each other, are respectively connected to the third and fourth switches **S3** and **S4**. The inductor L_r is connected to the first and second diodes **D1** and **D2** in order to prevent a reverse of resonance current I_L .

Each switch **S1**, **S2**, **S3** and **S4** can be formed with a metal oxide semiconductor field effect transistor (MOSFET), a reversal and parallel connected diode or an insulate gate bipolar transistor (IGBT).

FIG. 2 shows waveforms of the sustain driver having the energy recovery unit shown in FIG. 1. In FIG. 2, a waveform of the voltage V_p of the panel capacitor C_p , a waveform of the resonance current I_L , and each waveform $V_g(S1)$, $V_g(S2)$, $V_g(S3)$ and $V_g(S4)$ of switch **S1**, **S2**, **S3** and **S4**, are shown.

Referring to FIG. 2, the first and second sustain drivers **100** and **200** are operated by setting eight periods **T1** to **T8** as one cycle. The energy of $V_{sus}/2$, recovered from the panel capacitor C_p in the previous cycle, is stored in the external capacitor C_e of the first and second energy recovery units **10** and **20**.

In the first period of **T1**, a current path is formed between the external capacitor C_e and the panel capacitor C_p by

turning on the switch **S3**. At this time, the resonance current I_L is formed by the resonance operation of the inductor L_r and the panel capacitor C_p so that the voltage V_p of the panel capacitor C_p increases up to the sustain voltage V_{sus} . As mentioned above, during the period of **T1**, the voltage V_p of the panel capacitor C_p increases up to the sustain voltage V_{sus} by a current transferred from the external capacitor C_e and the resonance current I_L , however, in fact, a voltage drop Δ , i.e. an energy loss, is generated by a resistance of connection lines and by parasite resistances of devices in the PDP for the charging and discharging operations.

In the second period of **T2**, the voltage V_p of the panel capacitor C_p is sustained to the sustain voltage V_{sus} by turning on the switch **S1**. The switch **S3**, however, should be turned on for a $\frac{1}{2}$ resonance cycle, and the switch **3** can be either turned on or turned off after the $\frac{1}{2}$ resonance cycle.

In the third period of **T3**, the current path is formed between the panel capacitor C_p and the external capacitor C_e by turning off the switch **S1** and turning on the switch **S2**. The energy stored in the panel capacitor C_p by the resonance operation of the inductor L_r and the panel capacitor C_p is recovered to the external capacitor C_e .

In the fourth period of **T4**, the voltage V_p of the panel capacitor C_p is sustained to the ground voltage **0V** by turning on the switch **S2**. The switch **S4**, however, should be turned on for a $\frac{1}{2}$ resonance cycle, and the switch **4** can be either turned on or turned off after the $\frac{1}{2}$ resonance cycle. Further, a closed-loop is formed by turning on a sixth switch **S6** in the driving unit **22** of the second sustain driver **200** during the operation of four periods **T1** to **T4** in the first sustain driver **100**.

Thereafter, the operations of four periods, **T5** to **T8**, are performed in the second sustain driver **200**. At this time, the voltage V_p of the panel capacitor C_p becomes the negative voltage. The operations of the switches **S5** and **S6** are the same with the first and second switches of the first sustain driver **100**. A closed-loop is formed by turning on the second switch **S2** in the driving unit **12** of the second sustain driver **200** during the operation of four periods **T5** to **T8** in the first sustain driver **100**.

The power loss can be reduced by the conventional PDP comprising the energy recovery unit, and the panel capacitor C_p is charged and discharged with $\frac{1}{2}$ resonance of the inductor L_r and the panel capacitor C_p in the sustain drivers.

However, it is need to large area and high cost for manufacturing the sustain driver of the conventional PDP having the energy recovery unit because two energy recovery units are places symmetrically with the panel capacitor as a center.

SUMMARY OF THE INVENTION

It is, therefore, an object of the present invention to provide an apparatus of sustain driver in AC-type plasma display panel having energy recovery unit capable of reducing the area and cost.

In accordance with an aspect of the present invention, there is provide an apparatus of a sustain driver in an AC-type plasma display panel having an energy recovery unit, comprising: a first drive means for driving one electrode of a panel capacitor to a sustain voltage or a ground voltage; a second drive means for driving another electrode of the panel capacitor to a sustain voltage or a ground voltage; and a common energy recovery means. The common energy recovery means includes: an inductor connected to the one electrode of the panel capacitor and form a L-C resonance circuit with the panel capacitor; a first and second

external capacitors connected in series between the power source of the sustain voltage and the ground; and a switch means for selectively switching the L-C resonance circuit and the first and second external capacitors during the charge and discharge operation of the panel capacitor.

BRIEF DESCRIPTION OF THE DRAWINGS

The above and other objects and features of the instant invention will become apparent from the following description of preferred embodiments taken in conjunction with the accompanying drawings, in which:

The FIG. 1 is a circuit diagram showing a conventional weber-type sustain driver of the plasma display panel(PDP) having an energy recovery unit;

FIG. 2 is a diagram showing waveforms of operating the sustain driver in the PDP shown in FIG. 1;

FIG. 3 is a circuit diagram showing a sustain driver in the PDP having the energy recovery unit of the present invention; and

FIG. 4 is a diagram showing waveforms of the sustain driver in the PDP having the energy recovery unit shown in FIG. 3.

DETAILED DESCRIPTION OF THE PREFERRED EMBODIMENTS

In the present invention, a energy recovery unit is commonly connected to two sustain drivers. A first and second external capacitors are connected in serial between a power source of the sustain voltage V_{sus} and a ground. The first and second external capacitor are connected to one and another electrode of the panel capacitor, respectively, in order to supply and recovery energy in the charge and discharge operations.

Hereinafter, a sustain driver in the plasma display panel (PDP) having an energy recovery unit according to the present invention will be described in detail referring to the accompanying drawings.

FIG. 3 is a circuit diagram showing a sustain driver in a PDP having the energy recovery unit of the present invention.

In FIG. 3, the sustain driver of the PDP having the energy recovery unit includes a first driver **32** and a second driver **34** connected to a panel capacitor C_p representing the panel and a common energy recovery unit **30** for recovering the energy loss during the discharge operation of the panel capacitor and supplying the recovered energy to the panel capacitor. In the present invention, one energy recovery unit **30** is shared with two sustain drivers instead of using the separate energy recovery unit in each sustain driver.

The first driver **32** includes a pull-up switch Q_{yh} connected between the power source of the sustain voltage V_{sus} and the panel capacitor C_p in order to drive the panel capacitor C_p to the sustain voltage V_{sus} and a pull-down switch Q_{yl} connected between the ground and the panel capacitor C_p in order to drive the panel capacitor C_p to the ground voltage.

The second driver **34** includes a pull-up switch Q_{xh} connected between the power source of the sustain voltage V_{sus} and the panel capacitor C_p in order to drive the panel capacitor C_p to the sustain voltage V_{sus} and a pull-down switch Q_{xl} connected between the ground and the panel capacitor C_p in order to drive the panel capacitor C_p to the ground voltage.

The common energy recovery unit **30** includes an inductor L_r connected to the panel capacitor C_p for operating $\frac{1}{2}$

resonance, a first external capacitor Ce1 and a second external capacitor Ce2 connected in series between the power source of the sustain voltage and the ground in order to store recovered energy during the resonance operation of the inductor Lr and the panel capacitor Cp, a first and a second switches Qer1 and Qer2 connected in parallel between node A and the inductor Lr for switching the energy recovery path, a first and a second diodes D1 and D2 connected between each switch of Qer1 and Qer2 and the inductor Lr for preventing the reverse of the resonance current and two resistors R1 and R2 connected in series between the power source of sustain voltage Vsus and the ground in order to form a voltage divider. The first external capacitor Ce1 and the second external capacitor Ce2 are designed to get the same capacity values. However, such capacitors may not sustain the Vsus/2 value because the capacitors are sensitive under environmental circumstances such as its temperature. By forming the voltage divider using two identical resistors R1 and R2 in the circuit, the stable potential can be sustained in node A.

Each of switches Qer1, Qer2, Qxh, Qxl, Qyh and Qyl can be formed with a metal oxide semiconductor field effect transistor (MOSFET), reversely parallel-connected diodes or an insulate gate bipolar transistor (IGBT).

FIG. 4 is a diagram showing waveform of the sustain driver in the PDP having the energy recovery unit of FIG. 3. The waveform of the gate voltage Vg in each of switches Qer1, Qer2, Qxh, Qxl, Qyh and Qyl, the waveform of voltage Vp of the panel capacitor and the waveform of the current flowing in the inductor Lr are shown in FIG. 4.

In FIG. 4, the first driver 32 and the second driver 34 and the common energy recovery unit 30 are operated by setting eight periods T1 through T8 as one cycle. The energy of Vsus/2 recovered from the panel capacitor Cp in the previous cycle is stored in the first and second external capacitors Ce1 and Ce2 of the common energy recovery unit 30.

In the first period of T1, the voltage Vp of the panel capacitor Cp increases up to the sustain voltage Vsus by turning on the switch Qer1 and the switch Qxl in the second driver 34. That is, the second external capacitor Ce2, the switch Qer1, the first diode D1, the inductor Lr, the panel capacitor Cp and the switch Qxl in the second driver 34 form a closed-loop to flow resonance current I_L by the resonance operation of the inductor Lr and the panel capacitor Cp in order to charge the panel capacitor Cp up to the sustain voltage Vsus.

In the second period of T2, the voltage Vp of the panel capacitor Cp is sustained at the sustain voltage Vsus by turning on the switch Qer1 and turning off the switch Qyh in the driver 32. That is, the power source of sustain voltage Vsus, the switch Qyh in the first driver 32, the panel capacitor Cp and the switch Qxl in the second driver 34 form a closed-loop.

In the third period of T3, the voltage Vp of the panel capacitor is dropped to the ground voltage by turning off the switch Qyh in the driver 32 and turning on the switch Qer2. That is, the switch Qxl in the second driver 34, the panel capacitor Cp, the inductor Lr, the second diode D2, the switch Qer1 and the second external capacitor Ce2 form a closed-loop to flow resonance current I_L by the resonance operation of the inductor Lr and the panel capacitor Cp in order to discharge the panel capacitor Cp and recover the discharged energy to the second external Ce2.

In the fourth period of T4, the voltage Vp of the panel capacitor Cp is sustained to the ground voltage 0V for a predetermined time by sustaining the states of all the switches.

In the fifth period of T5, the voltage Vp of the panel capacitor Cp is dropped to -Vsus by turning off the switch Qxl and turning on the switch Qxh. That is, the first external capacitor Ce1, the switch Qxl, the panel capacitor Cp, the inductor Lr, the second diode D2 and the switch Qer2 form a closed-loop in order to charge the panel capacitor Cp.

In the sixth period of T6, the voltage Vp of the panel capacitor Cp is sustained to -Vsus by turning off the switch Qer2 and turning on the switch Qyl in the first driver 32. That is, the power source of the sustain voltage Vsus, the switch Qxh in the second driver 34, the panel capacitor Cp and the switch Qyl in the first driver 32 form a closed-loop.

In the seventh period of T7, the voltage Vp of the panel capacitor Cp is dropped to the ground voltage by turning off the switch Qyl and turning on the switch Qer1. That is, the second external capacitor Ce2, the switch Qer1, the first diode D1, the inductor Lr, the panel capacitor Cp, the switch Qxh in the second driver 34 form a closed-loop to flow resonance current I_L by the resonance operation of the inductor Lr and the panel capacitor Cp in order to discharge the panel capacitor Cp and recover the discharged energy to the second external Ce2.

In the eighth period of T8, the voltage Vp of the panel capacitor Cp is sustained the ground voltage 0V for a predetermined time by sustaining the sates of all the switches.

In the above mentioned description, the voltage divider formed with the two resistors is adopted to the PDP. However, such a voltage divider can be omitted.

As mentioned above, the PDP according to the present invention adopts one energy recovery unit, therefore it is possible to reduce area of panel drive circuit and cost.

While the present invention has been described with respect to the particular embodiments, it will be apparent to those skilled in the art that various changes and modifications may be made without departing from the spirit and scope of the invention as defined in the following claims.

What is claimed is:

1. An apparatus of a sustain driver in an AC-type plasma display panel having an energy recovery unit, comprising:
  - a first drive means for driving one electrode of a panel capacitor to a sustain voltage or a ground voltage;
  - a second drive means for driving another electrode of the panel capacitor to a sustain voltage or a ground voltage; and
  - a common energy recovery means, wherein the common energy recovery means includes:
    - an inductor connected to the one electrode of the panel capacitor and form a L-C resonance circuit with the panel capacitor;
    - a first and second external capacitors connected in series between the power source of the sustain voltage and the ground; and
    - a switch means for selectively switching the L-C resonance circuit and the first and second external capacitors during the charge and discharge operation of the panel capacitor.

2. The apparatus as recited in claim 1, wherein the switch means includes:

- a first switch and a second switch connected in parallel between the inductor and a contact point of the first external capacitor and the second external capacitor; and

a first diode and a second diode connected between the inductor and the first and the second switches, respectively, for preventing a reverse of the resonance current.

3. The apparatus as recited in claim 2, the first external capacitor and the second external capacitor have the identical capacity. 5

4. The apparatus as recited in claim 3, wherein the common energy recovery means includes a voltage stabilization means for stabilizing the voltages of the first external capacitor and the second external capacitor. 10

5. The apparatus as recited in claim 4, wherein the voltage stabilization means includes two resistors having the same resistance, connected in series between the power source of the sustain voltage and the ground. 15

6. The apparatus as recited in claim 2, wherein the first drive means includes:

a first pull-up switch connected between the power source of the sustain voltage and the panel capacitor; and

a first pull-down switch connected between the ground and the panel capacitor. 20

7. The apparatus as recited in claim 6, wherein the second drive means includes:

a second pull-up switch connected between the power source of the sustain voltage and the panel capacitor; and

a second pull-down switch connected between the ground and the panel capacitor.

8. The apparatus as recited in claim 7, wherein the second pull-down switch forms a closed-loop with the second external capacitor, the inductor and the panel capacitor during the charge and the discharge operations of the panel capacitor. 10

9. The apparatus as recited in claim 7, wherein the second pull-up switch forms a closed-loop with the first external capacitor, the inductor and the panel capacitor during the charge and the discharge operations of the panel capacitor. 15

10. The apparatus as recited in claim 8, wherein the second external capacitor stores recovered energy during the charge and the discharge operations of the panel capacitor. 20

11. The apparatus as recited in claim 10, wherein the first external capacitor stores recovered energy during the charge and the discharge operations of the panel capacitor.
